US00D917644S

(12) **United States Design Patent** (10) **Patent No.:** **US D917,644 S**
(45) **Date of Patent:** **** Apr. 27, 2021**

(54) **GOLF CLUB HEAD**

(71) Applicant: **KARSTEN MANUFACTURING CORPORATION**, Phoenix, AZ (US)

(72) Inventors: **Calvin S. Wang**, Chandler, AZ (US);
David A. Higdon, Cave Creek, AZ (US);
Murphy R. Alexander, Scottsdale, AZ (US)

(73) Assignee: **KARSTEN MANUFACTURING CORPORATION**, Phoenix, AZ (US)

(**) Term: **15 Years**

(21) Appl. No.: **29/700,018**

(22) Filed: **Jul. 30, 2019**

(51) LOC (13) Cl. **21-02**

(52) U.S. Cl.

USPC **D21/752**

CLAIM

(57) The ornamental design for a golf club head, as shown and described.

DESCRIPTION

FIG. 1 is a top perspective view of a golf club head;
FIG. 2 is a bottom perspective view of the golf club head of FIG. 1;
FIG. 3 is a top view of the golf club head of FIG. 1;
FIG. 4 is a bottom view of the golf club head of FIG. 1;
FIG. 5 is a front view of the golf club head of FIG. 1;
FIG. 6 is a rear view of the golf club head of FIG. 1;
FIG. 7 is a heel side view of the golf club head of FIG. 1;
FIG. 8 is a toe side view of the golf club head of FIG. 1;
FIG. 9 is a top perspective view of another embodiment of a golf club head;
FIG. 10 is a bottom perspective view of the golf club head of FIG. 9;
FIG. 11 is a top view of the golf club head of FIG. 9;
FIG. 12 is a bottom view of the golf club head of FIG. 9;
FIG. 13 is a front view of the golf club head of FIG. 9;
FIG. 14 is a rear view of the golf club head of FIG. 9;
FIG. 15 is a heel side view of the golf club head of FIG. 9; and,
FIG. 16 is a toe side view of the golf club head of FIG. 9. The broken lines shown form no part of the claimed design.

1 Claim, 10 Drawing Sheets
